ATTORNEY

UNITED STATES PATENT OFFICE

HERMAN SEIFFERT, OF NEW YORK, N. Y.

DESIGN FOR A PICTURE-FRAME.

SPECIFICATION forming part of Design No. 30,133, dated February 7, 1899.

Application filed January 11, 1899. Serial No. 701,886. Term of patent 3½ years.

To all whom it may concern:

Be it known that I, HERMAN SEIFFERT, a citizen of the United States, residing in the city, county, and State of New York, have invented and produced a new and original Design for Picture-Frames; and I do hereby declare that the following is a full, clear, and exact description of the same.

Reference is to be had to the accompanying drawing, which is a face view of a picture-frame, showing my new design.

As shown in the drawing, the leading or material feature of my design is the triangular form of the frame, having narrow stripes 1, 2, and 3 along its three sides, respectively, of a contrasted color or appearance. The stripe 1 is supposed to be red in color, the

stripe 2 white, the stripe 3 blue, and the enclosed triangular portion white.

It is apparent that this design is applicable as well to the tops of boxes and analogous articles.

Having described my design, what I claim as new, and desire to secure by Letters Patent, is—

The design for a picture-frame, as herein shown and described.

In testimony whereof I have hereunto set my hand the 18th day of November, 1898.

HERMAN SEIFFERT.

In presence of—

CLARENCE L. BURGER,
A. G. KENNEDY.
